UNITED STATES PATENT OFFICE

JACK C. CARLTON, OF SOUTHGATE, CALIFORNIA, ASSIGNOR TO A. LIPTON, DOING BUSINESS AS ALLIED METAL INDUSTRIES, OF INGLEWOOD, CALIFORNIA

DESIGN FOR A COMBINATION CURTAIN POLE AND CURTAIN SUSPENDING MEANS

Application filed August 4, 1930. Serial No. 36,543. Term of patent 3½ years.

To all whom it may concern:

Be it known that I, JACK C. CARLTON, a citizen of the United States, residing at Southgate, in the county of Los Angeles and State of California, have invented a new, original, and ornamental Design for a Combination Curtain Pole and Curtain Suspending Means, of which the following is a specification, reference being had to the accompanying drawing, forming part thereof.

The figure is a front elevation of the

combination curtain pole and curtain suspending means showing my new design. The rear elevation of the design is plain.

I claim:

The ornamental design for a combination curtain pole and curtain suspending means as shown and described.

Signed at Los Angeles, in the county of Los Angeles, and State of California, this 22nd day of July, 1930.

JACK C. CARLTON.
